UNITED STATES PATENT OFFICE.

WALTER R. ADDICKS, OF BOSTON, MASSACHUSETTS.

HEATER FOR HYDROCARBON LIQUIDS.

SPECIFICATION forming part of Letters Patent No. 448,214, dated December 23, 1890.

Application filed June 9, 1890. Serial No. 354,714. (No model.)

To all whom it may concern:

Be it known that I, WALTER R. ADDICKS, of Boston, county of Suffolk, State of Massachusetts, have invented an Improvement in Heaters for Hydrocarbon Liquids, of which the following description, in connection with the accompanying drawings, is a specification, like letters on the drawings representing like parts.

10 My invention relates to a heater to be used in the process of making gas from hydrocarbon liquids. These heaters have heretofore consisted of a coil or stack of pipes, through which the liquid to be heated passed, the said 15 pipes being all contained in a single drum, through which steam is permitted to pass so as to heat the liquid passing through the pipes and vaporize it.

The object of the present invention is to 20 produce a heater of a simpler and less expensive construction than those heretofore employed and more efficient in the treatment of the liquid, it also having its parts more accessible for cleaning or repairs.

25 In constructing my invention I employ in a heater composed of a number of lengths of pipe, through which the hydrocarbon liquid flows, the outlet end of each length, with relation to the flow of liquid through it, being 30 connected with the inlet end of the next length, so that the liquid flows continuously throughout the entire series of connected lengths. Each length of pipe is surrounded and inclosed by a chamber, which may consist of 35 another length of pipe the internal diameter of which is somewhat greater than the external diameter of the pipe inclosed by it, the space between the said pipes being tightly closed at both ends of the outer pipe—as, for 40 example, by a stuffing-box of usual construction—and steam being admitted into the space between the said pipes, and thereby surrounding the inner pipe and acting to heat the liquid flowing through it. In order to insure efficiency of operation the successive lengths of 45 pipe through which the liquid flows are of increased diameter or bore, so that as the liquid vaporizes and expands the duct will be of correspondingly-increased sectional area, so that 50 the velocity of the flow of the fluid will not increase as it would if the pipe were of uni-

form bore. The several lengths of pipe, with their surrounding jackets, are placed near together, and the short connected portions are preferably provided with couplings, so that 55 any one length can be readily detached when necessary for cleaning or can easily have another length substituted for it in case it has become damaged in any way. The lengths of pipe are shown as placed in vertical position, 60 and under each length there is a collecting-receptacle, into which any solid or sedimentary matter carried by the fluids will be received, thus keeping the main duct free.

The invention consists in a heater for hydrocarbon liquids constructed and arranged substantially as herein pointed out and claimed.

Figure 1 represents a heater embodying this invention; Fig. 2, a detail showing a portion 70 of one of the ducts in longitudinal section.

The liquid to be treated is taken from a tank or reservoir *a*, constructed or arranged to deliver into a pipe *b* under substantially uniform pressure, from which the said liquid passes 75 through a meter *c* for regulating the quantity of flow and is conveyed by the pipe *d* to the heater *A*. The said heater consists of a number of lengths of pipe *e* *e'* *e''*, &c., the outlet end of one being connected with the inlet end 80 of the next by short connecting-pieces *f* *f'*, &c., preferably including couplings or union joints *g*, to enable one length to be readily separated from the next. Each length is surrounded by a wall or tube *h*, larger than the 85 inclosed pipe *e*, and having the space between it and the inclosed pipe closed at each end, as represented at *h*², thus forming a jacket or chamber around each length of pipe, which space is supplied with live steam from a pipe 90 *i*, having branches *i*² (see Fig. 2) that enter the jackets near their upper ends. The water of condensation escapes through a pipe *i*³, connected by similar branches with the jackets near their lower ends. The said branches that 95 connect the pipes *i* and *i*³ with the jackets are preferably provided with coupling or union joints, so as to facilitate the separation of one jacket and its inclosed length of pipe from the rest when required. Below each length of 100 pipe is provided a drip or sediment receptacle *k*, which will receive any sedimentary ma-

terial that may be carried along by the liquid or fluid passing through the pipes $e e^2$, &c., and said receptacle may be emptied from time to time when required.

5 The pipes $e e^2 e^3$, &c., increase in diameter in the direction of the pressure of fluid through them, as shown, for the reason before explained.

From the last pipe of the heater the fluid 10 may be conveyed through the pipe m to a gas-machine or carburetor.

By this construction a far more efficient heater may be produced than those in which the entire duct or pipe for the liquid to be

15 heated is contained in a single jacket, as the liquid will be gradually heated in passing from one length of the heater-pipe to the next and will also expand in volume, but owing to the increase in sectional area of the next duct will 20 flow slowly through the same and become further heated, this operation continuing until the liquid has passed through the entire set of pipes, the last of which it will enter in an already highly-heated condition, and the

25 steam which acts upon the liquid in the last length of pipe will operate efficiently, as its temperature is not reduced by the cooler liquid passing through the preceding section of pipe, as is the case when the entire set of pipes 30 through which the liquid passes are heated by

steam in a single surrounding jacket or chamber or passing from one jacket to another, as has been proposed in heating apparatus.

The sectional construction enables another section to be readily removed and replaced by 35 another if it needs renewal or repairs.

I claim—

A heater for heating oil, composed of a number of lengths of pipe of progressively-increasing diameter from the inlet-pipe to the outlet- 40 pipe to compensate for the expansion of the fluid being heated without accelerating its relative flow, and connected end to end and forming a continuous duct of severable parts, combined with an independent steam-jacket 45 for each length of pipe, and an independent steam - inlet, and an independent outlet for water of condensation for each jacket, thereby forming a continuous duct for the oil to be heated, heating each length of pipe independ- 50 ently and at essentially the same temperature, and also draining each jacket independently, substantially as described.

In testimony whereof I have signed my name to this specification in the presence of two sub- 55 scribing witnesses.

WALTER R. ADDICKS.
